(57) CLAIM

The ornamental design for a golf ball, as shown and described.

DESCRIPTION

FIG. 1 is a front elevation view of a golf ball, showing our new design;

FIG. 2 is a rear elevation view thereof;

FIG. 3 is a top plan view thereof;

FIG. 4 is a bottom plan view thereof;

FIG. 5 is a left side elevation view thereof;

FIG. 6 is a right side elevation view thereof; and,

FIG. 7 is a top, left side perspective view thereof.

The broken lines shown in the figures depict portions of the golf ball that form no part of the claimed design. The broken lines that illustrate the text and arrow features on the golf ball form no part of the claimed design.

1 Claim, 7 Drawing Sheets
